UNITED STATES PATENT OFFICE.

JOHN F. POOL, OF MOUNT CARMEL, ILLINOIS.

FASTENER FOR MEETING-RAILS OF SASHES.

SPECIFICATION forming part of Letters Patent No. 368,004, dated August 9, 1887.

Application filed April 12, 1887. Serial No. 234,514. (No model.)

To all whom it may concern:

Be it known that I, JOHN F. POOL, of Mount Carmel, in the county of Wabash and State of Illinois, have invented a new and Improved 5 Window-Fastener, of which the following is a full, clear, and exact description.

The object of this invention is to provide a sash-fastener whereby the sash may be securely locked in a closed position, and whereby the 10 sash may be held partially open, as will be hereinafter more fully explained, and specifically pointed out in the claims.

Reference is to be had to the accompanying drawings, forming a part of this specification, 15 in which similar figures of reference indicate corresponding parts in all the views.

Figure 1 is a view of the inner face of a window-sash provided with my improved form of fastener, the frame at the top of the window- 20 casing being broken away to disclose the arrangement of the catch and keeper employed to hold the upper sash in a raised position. Fig. 2 is a sectional view taken on line *x* *x* of Fig. 1; and Fig. 3 is a sectional view of a portion of the upper sash and of the fastening- 25 catch that is carried by the upper cross-bar of the lower sash, the case of said catch being shown in section.

In the drawings, 10 represents the window- 30 casing, 11 the upper and 12 the lower sash, which sashes are provided with a heavy central rail, 13. With such sashes as those illustrated in the drawings the parts of the fastener arranged in connection with the upper 35 sash are secured to said heavy central rail, 13, while the parts of the fastener carried by the lower sash are secured to the upper cross-bar of the sash above its central rail. However, with windows having light central rails the 40 fastening devices would be secured to the side rails of the sash.

The fastener consists of a catch, 14, that is mounted within a case, 15, the catch being supported by a pivot-pin, 16, which carries a 45 forwardly-extending spring, 17, said spring resting in an aperture, 18, that is formed in the catch, and tending to hold the catch in the position in which it is shown in Fig. 3. The casting of this catch is secured to the upper cross- 50 bar of the lower sash, in position so that the point of the catch will be in line with the centers of a series of castings, 19, that are secured

to the upper sash, these castings 19 being formed with upper and lower curved arms, 2, and with upper catch-recesses, 3, and lower 55 catch-recesses, 4. As many of these castings may be employed as may be deemed practicable.

To the upper cross-bar of the sash 11, I connect a catch, 20, that is arranged to enter a recess, 21, that is formed in the upper part of the window-casing, the point of said catch passing through a central slot or opening that is formed in a plate, 22, arranged as illustrated in Fig. 1 of the drawings. This catch 20 is 65 provided with a lever-arm, 23, which is held loosely against the upper cross-bar of the sash 11 by a staple, 24, and just beyond the pivot 5, upon which the catch is mounted, I form a recess, 6.

When it is desired to lock the window-sash in the closed position, the upper sash is moved upward until its catch 20 engages with the plate 22. Then the lower sash is closed and the point of the catch 14 is brought into engagement with the recess 4 of the lower casting, 19. A pin, 60, is then inserted in proper apertures formed in the casing 15, and being so inserted will act to hold the catch in the position in which it is shown in Figs. 1 and 3— 70 75 80 that is, to hold the point of the catch against the face of the lower arm, 2, of the lower casting.

When it is desired to raise the window, the pin 60 is removed, the catch 14 is grasped by 85 its handle or knob 7 and moved in the direction of the arrow, shown in Fig. 3, being in this way freed from engagement with the recess 4 of the lower casting. The sash 12 may then be raised, and for convenience I prefer 90 to provide said sash with a knob or handle, 28. After the sash 12 has been slightly raised the catch may be released, and the spring 17 will then force the point of the catch to bear against the convex face of the upper arm of 95 the lower casting. As the sash is raised the point of the catch 14 will strike against the convex face of the lower arm of the next casting above, and as the upward movement of the sash continues the spring 17 will force the 100 point of the catch into engagement with the recess 3 of the last-mentioned casting; and if at this time the hold upon the sash 12 be released it will be supported in the position to

which it has been moved. When it is desired to lower the upper sash, the lower sash is raised until the point of the catch 14 has passed the upper casting, 19, and entered the recess 5 6 of the casting 20, when, if a slight upward movement is imparted to the lower sash, the catch 20 will be disengaged and the upper sash will be free to drop as the lower sash is moved downward. When it is desired to support the upper sash in a lowered position, the catch 14 may be brought into engagement with any one of the recesses 4. It will be noticed that the points of the arms 2 extend beyond the central lines of the castings 19, so that in 15 moving the lower sash upward the catch 14 will freely pass all of the castings, moving at this time upon the left-hand face of the lower arm, and in lowering the upper sash the catch will pass upon the right-hand side of the upper 20 arm.

This fastening entirely obviates the necessity of counterbalancing weights, and consequently materially cheapens the cost of hanging the sash; and it will be seen that the fastening may be applied to most any form of 25 window without material alteration.

Although I have described the parts 19 as being castings, it will of course be understood that they might be stamped in sheet 30 metal or otherwise formed.

Having thus fully described my invention, I claim as new and desire to secure by Letters Patent—

1. The combination, with a horizontally-oscillating catch and a spring for returning it to its normal position at right angles to the plane of the sash, of a vertical plate or casting recessed at top and bottom, and having arms inclined or curved in opposite directions across 40 the path of the free end of the catch, one of said arms projecting upwardly from one side over the recess in the top of the plate and the other downwardly from the other side below

the recess in the bottom of the plate, substantially as set forth. 45

2. The combination, with a horizontally-oscillating catch having a longitudinal slot, and a spring secured to the catch-pivot and entering the slot to hold the catch at right angles to the plane of the sash, of the plate or casting recessed at top and bottom and having arms inclined or curved in opposite directions across the path of the free end of the catch, one of the said arms projecting upwardly from one side over the recess in the top of the plate 55 and the other downwardly from the other side below the recess in the bottom of the plate, substantially as set forth.

3. The combination, with the fastener for the meeting-rails, of the catch for locking the top rail of the upper sash to the top of the window-casing, said catch having an arm extending into the upward path of that part of the fastener which is on the lower sash, whereby when the lower sash is raised the said catch 65 will be released, substantially as set forth.

4. A fastening mechanism for sashes, comprising the horizontally-oscillating meeting-rail fastener having a spring holding it normally at right angles to the top rail of the 70 lower sash, the plates or castings on a vertical rail of the upper sash inclined or curved in opposite directions on their side edges at opposite sides of their centers and recessed in their opposite sides, the angular catch pivoted 75 to the top rail of the upper sash and having a recess in the lower edge of its horizontal arm to receive the free end of the meeting-rail fastener and in a vertical alignment with the normal position thereof, and the catch- 80 plate on the casing for the vertical arm of the catch, substantially as set forth.

JOHN F. POOL.
